JOHN JOSEPH CHARLES SMITH, OF SOMERVILLE, ASSIGNOR TO THE METALLIC COI
PRESSION CASTING COMPANY, OF BOSTON, MASSACHUSETTS, ASSIGNOR TO RU
SELL & ERWIN MANUFACTURING COMPANY, OF NEW BRITAIN, CONNECTICUT.

Design No. 4,135, dated June 7, 1870.

DESIGN FOR A DOOR-KNOB.

The Schedule referred to in these Letters Patent and making part of the same.

I, JOHN JOSEPH CHARLES SMITH, of Somerville, in the county of Middlesex and State of Massachusetts, have invented and produced a new and original Design for a Door-Knob, of which the following is a specification.

The nature of my design is represented in the accompanying photographic illustration, to which reference is made.

I claim the design for a door-knob, substantially above set forth.
